UNITED STATES PATENT OFFICE.

SAMUEL C. BARR, OF CHILlicothe, OHIO.

EYE-TESTING MACHINE.

1,266,090.

Specification of Letters Patent.

Patented May 14, 1918.

Application filed April 27, 1917. Serial No. 165,010.

To all whom it may concern:

Be it known that I, SAMUEL C. BARR, a citizen of the United States, residing at Chillicothe, in the county of Ross and State 5 of Ohio, have invented certain new and useful Improvements in Eye-Testing Machines, of which the following is a specification.

This invention relates to eye testing machines and is particularly designed as an attachment to the improved structure shown 10 in my co-pending application, Serial Number 133,546, filed November 27, 1916.

The main object of this invention resides in a structure whereby the prospective purchaser of eyeglasses, may also test the fittings such as the frames or nose pieces which go therewith. In this connection, my invention resides in the combination with a mirror, of a plurality of test frames arranged 20 to be successively brought into position to rest upon the nose of the prospective purchaser so that the latter may have a clear vision of the fit of the same.

A further object of my invention resides 25 in combining with the above, a resting structure against which the prospective purchaser may place his face to permit a yielding adjustment with respect to any of the frames. In other words, this latter structure is provided 30 for the convenience of the prospective purchaser.

Other objects of my invention become 35 more apparent after a further detailed description of the accompanying sheets of drawings, in which similar characters of reference designate corresponding parts, and in which:

Figure 1 is a front elevation of my improved type of testing machine,

40 Fig. 2 is a cross section taken on line 2—2 of Fig. 1, and,

Fig. 3 is a top plan view of the structure shown in Figs. 1 and 2.

My invention is designed to be supported 45 from any preferred structure such, for instance, as the machine shown in my pending application referred to above, which may be designated in its entirety by the reference numeral 1. This structure 1 is provided 50 with a pair of pierced ears 2 which are designed to coöperate with similar ears 3 upon the main framework and through which the pivot rod 4 is designed to pass. This main framework comprises a pair of rear up- 55 standing rods 5 connected at their upper and lower ends by means of a pair of headers

6 and a pair of vertically arranged front channel members 7, connected to the bars 5 by means of cross tie pieces 8. Rotatably journaled in each upper and lower tie piece 60 8 are a pair of sprockets 9, each pair being rigidly connected to each other by means of a plurality of cross pieces 10, as is shown. A pair of endless chains 11 are designed to pass over these sprockets 10 in the manner 65 shown, so that the forward strand of each chain operates within its respective channel 7 to prevent it from flexing, for a purpose to be described. At predetermined intervals, these chains are provided with suitable links 70 12 carrying studs 13 upon which the spectacle frames 14 are mounted. Any desired number of spectacle frames may be carried by the chains in this manner, but care should be taken so that no two frames will be in 75 horizontal alinement when one is in the proper testing position. These chains are operated by means of the handle 15 which is rotatably journaled upon the tie piece 16 and which carries a sprocket 17 operating within 80 the cut-out portion 18 of one of the channels 7. Rotation of this hand wheel 15 causes a vertical movement of one of the endless chains 11 and because of the rigid connection between the sprockets 9 due to the cross 85 pieces 10, both chains are given a similar movement. This correspondingly moves the various spectacle frames 14 to the desired testing position.

Properly located in the rear of the testing 90 frame is a mirror 19 which is also preferably pivotally hung along one edge, as shown at 20 to the supporting structure 1 and is connected with the testing frame by means of the connecting rod 21, this latter 95 being pivotally mounted to the mirror at 22 and to the framework at 23. Thus, when the main framework is swung around into operative position, it also swings the mirror 19 around to this operative position, and 100 thus, as the successive spectacle frames are brought to testing position, the prospective purchaser may view the effect in the mirror 19.

In order to provide a resting structure for 105 the face of the purchaser, I have provided a pair of bowed strips 24, which latter are preferably supported upon one end of the spring strips 25, these strips being rigidly mounted at their opposite ends, as shown at 110 26 to the channel frame pieces 7. Because of the resiliency of the strips 25, the pro-

spective purchaser may adjust himself in the proper position, by pushing either one or both of the bowed strips 24 inwardly. In this manner, the proper resting position of 5 the spectacle frames upon the nose may be had.

From the foregoing description, it will be apparent that I have provided a structure wherein all of the spectacle frames mounted 10 upon the endless chains may be brought into proper position for testing, the effect being viewed in the mirror 19. When the desired frame has been ascertained, it remains only for the purchaser to ascertain the style or 15 some distinguishing mark thereon to receive the proper article.

What I claim, is:

1. In an eyeglass frame testing machine, the combination with a fixed support, of a 20 frame pivotally connected with said support, an endless eyeglass frame carrying chain rotatably mounted within said frame, a hingedly supported mirror movable in unison with said frame, and means for re- 25 volving said chain to selectively align the chain carried eyeglass frames with said mirror.
2. In an eyeglass testing machine, a mirror, a plurality of lens frames movably 30 mounted with respect to said mirror to bring any to a testing position opposite said mirror, and a resting structure against which the face is placed, said structure permitting a yielding adjustment with respect to any of 35 said frames.
3. In an eyeglass frame testing machine, the combination with a fixed support, of a

frame pivotally connected with said support, an endless eyeglass frame carrying chain rotatably mounted within said frame, 40 a hingedly supported mirror movable in unison with said frame, and means for re-volving said chain to selectively align the chain carrying eyeglass frames with said mirror and a face resting structure connected with said frame and resiliently movable toward the latter.

4. In an eyeglass testing machine, a mirror, a framework located in front of said mirror, a pair of endless chains carried by 50 said framework, a plurality of lens frames supported between said chains, means for moving said chains to bring any of said frames in front of said mirror, and means 55 for guiding the front strands of said chains to prevent their flexing when said frames are being tested.

5. In an eyeglass testing machine, a mirror, a framework located in front of said mirror, a pair of endless chains carried by 60 said framework, a plurality of lens frames supported between said chains, a channel guide piece for the front strand of each chain, and an upper and lower resilient resting structure carried by said framework 65 against which the face is placed, said resting structure permitting a yielding adjustment with respect to any of said frames.

In testimony whereof I affix my signature in presence of two witnesses.

SAMUEL C. BARR.
